UNITED STATES PATENT OFFICE.

LOUIS JAY KASS, OF NEW YORK, N. Y., ASSIGNOR TO FERDINAND STRAUSS, OF NEW YORK, N. Y.

DESIGN FOR A TOY.

Application filed January 10, 1925. Serial No. 11,983. Term of patent 7 years.

To all whom it may concern:

Be it known that I, LOUIS JAY KASS, a citizen of the United States of America, residing at New York city, county and State of New York, have invented a new, original, and ornamental Design for a Toy, of which the following is a specification, reference being had to the accompanying drawing, forming part hereof, in which the figure illustrates a perspective view of a toy showing my new design.

I claim:—

The ornamental design for a toy as shown. Signed at New York city, N. Y., this 9th day of January, 1925.

LOUIS JAY KASS.

Witnesses:

JOHN J. LYNCH,
MAURICE BLOCK.
